BRAKE SHOE

Filed April 11, 1927

UNITED STATES PATENT OFFICE

MONTGOMERY W. MC CONKEY, OF SOUTH BEND, INDIANA, ASSIGNOR TO BENDIX BRAKE COMPANY, OF CHICAGO, ILLINOIS, A CORPORATION OF ILLINOIS

BRAKE SHOE

Application filed April 11, 1927. Serial No. 182,684.

This invention relates to brake shoes, and is illustrated as embodied in an internal expanding automobile brake of the three-shoe type. An object of the invention is to provide for easily assembling the brake, by arranging one, or preferably both, of the end shoes with a radial slot (shown as an open slot facing toward the outside of the shoe) which can readily be mounted on the pivot 10 for the shoe.

In the illustrated arrangement, the central shoe (shown as anchored at one end) is formed with two stiffening webs connected and braced apart by members which also serve as pivots for the end shoes. The shoe at the end next the anchor of the central shoe may be formed, as shown, with an oppositely-facing slot affording clearance for the anchor.

Another feature of the invention relates to the construction of the end shoe, especially as to the strengthening of the arm projecting at the end of the shoe and formed with a slot or other opening for a pivot.

The above and other objects and features of the invention, including various novel combinations of parts and desirable particular constructions, will be apparent from the following description of one illustrative embodiment shown in the accompanying drawings in which:

Figure 1 is a vertical section, broken away at the top, through the brake just inside the head of the brake drum, showing the shoes in side elevation;

Figure 2 is a side elevation of the parts of the shoes appearing in Figure 1, but detached from each other;

Figure 3 is a partial section on the line 3-3 of Figure 1, showing the anchorage of the brake;

Figure 4 is a section through the end of the primary end shoe, on the line 4-4 of Figure 2;

Figure 5 is a section through the auxiliary end shoe, on the line 5-5 of Figure 2;

Figure 6 is a section through the central or secondary shoe, on the line 6-6 of Figure 2, showing the pivot on which the auxiliary end shoe is mounted; and

Figure 7 is a partial elevation showing the

connected ends of the primary and secondary shoes, looking in the direction of the arrows 7-7 in Figure 1.

The brake selected for illustration includes a rotatable drum 10, at the open side of which is arranged a suitable support such as a backing plate 12, and within which are arranged a primary shoe 14, a secondary shoe 16, and an auxiliary shoe 18, the three shoes constituting the friction means of the brake. Shoes 14 and 18 are forced apart, to apply the brake, against the resistance of a return spring 20, while shoe 16 is applied by shoe 14 against the resistance of an auxiliary spring 22. The present invention relates to the construction and arrangement of the shoes of the brake.

The secondary shoe 16 comprises an outer band or rim 24, to which the lining 26 is attached by rivets or otherwise, and two stiffening webs 28 and 30 which are welded (by arc or spot welding), at their outer edges, to the inner face of band 24. Webs 28 and 30 are extended, at the ends opposite shoe 14, to form projecting arms anchored on a pivot 32 carried by the backing plate 12. A bushing 34 serves as a spacer between these arms, and may be welded to them at its ends to serve as a bearing embracing the pivot.

Two bolts 36 and 38, passing through spacing sleeves 40 (which may be welded at their ends to webs 28 and 30 if desired) serve to brace the stiffening webs apart, and also serve as pivots for the lower ends of shoes 14 and 18. Spaced eccentrics 42 on a spindle 44 (carried by the backing plate 12) engage sleeve 40 of bolt 38, when the brake is released, so that spring 22 cannot twist the shoe sidewise in case of any looseness at the anchor 32.

Shoe 14 consists of an outer band or rim 46 carrying the lining 48, and to which is welded a stiffening web 50. At its lower end, web 50 is extended as a projecting pivot arm formed with a radial opening or slot 52 opening toward the outside of the shoe and seated on the pivot formed by bolt 38 and its sleeve 40. The end of this arm is reinforced by plates 54 welded to the sides of web 50, and formed with slots registering with slot 52,

thus providing a triple-width bearing surface engaging the pivot and obviating the need of any separate bushing. The end of web 50 is straddled by the two stops 42.

Shoe 18 comprises a band or rim 56 for the lining 58, and a stiffening web 60 welded thereto and extending downwardly as a projecting pivot arm reinforced by welded plates or stampings 62. The arm portion of web 60, and the plates 62, are formed with registering openings or radial slots 64, facing toward the outside of the shoe and serving as a bearing embracing the pivot formed by the bolt 36 and its sleeve 40. Plates 62 extend upwardly past the end of the rim 56, i. e. past the end of the friction face of the shoe, and together with web 60 are provided with registering openings or radial slots 66, shown facing toward the inside of the shoe, and wide enough to afford ample clearance for the anchor 32. Thus plates 64 have an auxiliary function in reinforcing the part of shoe 18 which is weakened by the opening necessary to clear the anchor.

While one illustrative embodiment has been described in detail, it is not my intention to limit the scope of the invention to that particular embodiment, or otherwise than by the terms of the appended claims.

I claim:

1. A brake shoe comprising a stiffening web extending at one end of the shoe beyond the friction face as a projecting arm, and reinforcing means for said arm from substantially the end of the arm back past the end of the friction face, said arm being formed with a radially-arranged open slot for direct engagement with a pivot.

2. A brake shoe having a stiffening web extending beyond the friction face of the shoe as a projecting arm and formed with a radial slot at the end of the arm which opens toward the outside of the shoe and with a radial slot near the end of the friction face which opens toward the inside of the shoe.

3. A brake shoe having transverse pivots near its opposite ends, and constructed and arranged to be mounted on a pivot at one end, in combination with two shoes arranged at opposite ends of the first shoe, and each of which is formed with an arm overlapping the end of the first shoe and formed with a radial slot seated directly on the corresponding one of said pivots.

4. A brake shoe having transverse pivots near its opposite ends, in combination with two shoes arranged at opposite ends of the first shoe, and each of which is formed with an arm overlapping the end of the first shoe and formed with a radial slot seated directly on the corresponding one of said pivots.

5. A brake shoe having transverse pivots near its opposite ends, in combination with two shoes arranged at opposite ends of the first shoe, and each of which is formed with

an arm overlapping the end of the first shoe and formed with an open radial slot facing toward the outside of the shoe and seated directly on the corresponding one of said pivots.

6. A central shoe having two spaced stiffening webs, members near opposite ends of the shoe connecting said webs and bracing them apart and also serving as pivots, in combination with two end shoes having at their ends open radial slots facing toward the outside of the shoes and directly pivoted on said members.

7. A brake comprising, in combination, at least two shoes arranged end to end, a pivot connecting adjacent ends of the shoes, a pair of stops spaced apart from each other and engageable with said pivot, and a spring arranged to urge the pivot against the stops.

8. A brake comprising, in combination, at least two shoes arranged end to end, a pivot connecting adjacent ends of the shoes, a pair of connected and simultaneously-adjustable stops spaced apart from each other and engageable with said pivot, and a spring arranged to urge the pivot against the stops.

9. A brake comprising, in combination, a pair of pivotally-connected shoes, one of which is anchored at one end, positioning means for the connected ends of the shoes including two stops spaced apart from each other crosswise of the shoes and serving to prevent twisting of the connected ends as well as to determine their radial position, and yielding means urging said ends toward the position determined by said stops.

10. A brake shoe having at one end spaced portions connected and braced by a member adapted to serve also as a pivot, in combination with another shoe formed at its end with an open radial slot facing toward the outside of the shoe and mounted on said pivot member.

11. A brake shoe having at one end spaced portions connected and braced by a member adapted to serve also as a pivot, in combination with another shoe formed at its end with a radial slot mounted on said pivot member.

12. A brake shoe anchored at one end and having a pivot at its other end, in combination with another shoe formed with an open radial slot facing toward the outside of the shoe and mounted on said pivot.

In testimony whereof, I have hereunto signed by name.

MONTGOMERY W. McCONKEY.
